UNITED STATES PATENT OFFICE.

LEONARD J. FROHN, OF NEW YORK, N. Y.

BACKING-MACHINE FOR BOOKS, TABLETS, AND THE LIKE.

1,304,760.

Specification of Letters Patent. Patented May 27, 1919.

Application filed April 10, 1916. Serial No. 90,035.

To all whom it may concern:

Be it known that I, LEONARD J. FROHN, a subject of the Emperor of Germany, and a resident of the city of New York, borough 5 of Manhattan, county and State of New York, have invented certain new and useful Improvements in Backing-Machines for Books, Tablets, and the like, of which the following is a specification.

10 This invention relates to machines for applying adhesive tape to the edges of assembled sheets in process of forming the same into a book, pad, tablet or the like, with more particular reference to mechanism in 15 such machines for insuring exact correspondence or adjustment in position of the edges of the superposed sheets to be taped, and to mechanism for insuring more nearly perfect uniformity in the taping operation, 20 having in view a more uniformly dependable, satisfactory and otherwise improved product.

The present invention, while capable of adaptation to many known types of taping 25 machines, is more particularly designed for application to a machine such as that shown and described in patent to Joseph Hren, No. 1,252,114, dated January 1, 1918, wherein the piles of assembled sheets to be taped are 30 successively fed into the machine, a continuous tape with a suitable adhesive thereon being applied to the edges of each advancing pile of sheets, and a cut-off mechanism being provided to automatically sever the tape- 35 strip between the taped books or pads prior to final discharge or ejection of the finished or partially finished work.

Where these piles of assembled sheets are 40 consecutively fed into the machine by hand, it will be apparent that in spite of the employment of suitable guiding means and the exercise of the greatest care, the edge of each pile to be taped will not be invariably advanced through the taping mechanism with 45 said edge parallel to the direction of advancing movement. As it is important, if not essential, that the edges of the superposed sheets be in practically perfect register and the edge of each sheet contact with the adhesive tape, which is folded over and pressed 50 against the top and bottom sheets of the pile,

it will be apparent that in bringing together said sheet-edges and tape in the tape-applying operation, some means should be provided to automatically insure continuous 55 contact between the tape and the edge of the pile of sheets, irrespective of slightly improper positioning of each pile of sheets by the operative.

Furthermore, in folding over the top portion of the tape and applying the same to the top sheet of the pile, it has been found that best results are obtained through the employment of a rotary brush, such as that shown and described in the Hren patent, 60 65 aforesaid, but it will be noted that while the bristles on one side of said brush move in a direction which causes them to tend to stretch the tape, smooth out the same on the top of the pile, and yieldingly press it down upon the top sheet, the bristles on the other side of said brush have a reverse or undoing tendency, on which account the brush is tilted or inclined for the purpose of elevating the ends of the bristles on one side thereof sufficient 70 75 to clear the pressed tape, leaving effectively operative only the bristles on the side of said brush which are moved toward the edge of the tape. It has been found, however, that if the tilt or inclination of the brush is sufficient to insure the desired clearance of the tape by the bristles on one side thereof, the desired effect on the other side thereof is minimized. I have, therefore, found it desirable—if not essential to best results—to 80 85 provide auxiliary or supplemental means for insuring the clearance to which I have referred above.

Furthermore, tape-pressing means other than the brush have been found desirable, in 90 order to produce not only a product which is compact, but a product to which the tape has been evenly and firmly applied.

The principal object of the present invention is the provision of means, in connection 95 with a taping machine of the character to which I have referred, for performing the desirable functions set forth above, and to provide a machine which embodies other minor improvements to the end of insuring 100 a uniformly high grade product.

My invention will be more readily under-

stood by reference to the accompanying drawings, forming a part of this specification, in which—

Figure 1 is a side elevation of the top portion of a taping machine embodying my invention;

Fig. 2 is an enlarged fragmentary top plan view thereof;

Figs. 3 and 4 are enlarged fragmentary sections taken substantially on the lines 3—3 and 4—4, respectively, of Fig. 2, and

Fig. 5 is an enlarged fragmentary section taken substantially on the line 5—5 of Fig. 1.

Referring now to the drawings in detail, numeral 7 designates the top of a work table supported by the legs 8. These legs also provide a frame for the support of mechanism for applying an adhesive to one side of a strip of tape 9, which is being continuously unrolled from a reel thereof, or for moistening a dry adhesive which has already been applied to one side of said tape. This gumming or moistening mechanism is not shown in the drawings, as it forms no part of the present invention, but a practical and convenient form thereof is shown and described in detail in the patent to Hren, aforesaid. For the purpose of this description, it will suffice to state that from the gumming or moistening device, the tape 9 is directed upwardly over the driven roller 10 which advances said tape and delivers the same to and upon the curved guide-plate 11, suitably secured at the edge of the table top. This guide plate 11 is gradually transversely curved or bent upwardly to form a substantially vertical portion 12 at the far end thereof, and the tape 9 is directed over the roller 10 in such manner that a substantial portion of one edge thereof travels along the horizontal portion of the end of the plate 11, while the major portion thereof is upwardly directed by the vertical portion 12 of said plate, giving the advancing tape a substantially L-shaped cross-sectional configuration, with the upper edge thereof projecting above the top of the pile of sheets to be taped.

The edge of the table top 7 is provided with a vertical guide plate 13, against which the edge of each pile of superposed sheets to be taped is adjusted by hand prior to feeding said pile, in the direction of the arrow, between the presser belt 14, mounted upon the outer face of the endless chain 15, and a lower belt 14' carried on the outer face of the endless chain 15'. The chain 15 passes over the sprocket wheels 16 and 17, the latter being provided with a bevel-gear 18 in mesh with a bevel-gear 19 on the driving shaft 20, and the chain 15' passes over the sprocket wheels 16' and 17', the latter carrying a bevel-gear 18' in mesh with a similar gear 19' on said driving shaft 20.

These belt-faced chains 15 and 15' are located back of the path of movement of the tape 9 through the machine, and therefore do not interfere in any way with the taping operation. They are adjustable with reference to each other to engage and advance the work in the usual manner.

The under side of the edge of the pile of advancing sheets to be taped is thus passed over the horizontally disposed edge of the advancing tape, against which the pile is pressed and the pile compressed to more compact form by the flat leaf-spring 21 suitably located for this purpose. That portion of the tape which has been longitudinally folded at substantially right angles to said horizontally disposed portion, is now in position for folding the top edge thereof over the top sheet of the pile. It may be, however, that the pile of blanks to be taped is for some reason improperly directed into the taping mechanism, and if this is the case the registering edges of the sheets of the pile will not be brought into contact with the vertical portion of the adhesive tape throughout the whole extent of said edges, and the taped book or pad will therefore be imperfect and unsatisfactory. To effect substantially continuous contact, in spite of careless or faulty manual feeding, and to insure better registration of continuous edges of the sheets of the pile, I mount upon the table top 7 a bracket 22 carrying the pin or post 23, upon which is adjustably mounted the split collar 24 to which is secured the resilient arm 25 spring-pressed in the direction of the table top. This spring arm 25 is preferably of leaf-spring form, and the upper edge of the free end thereof is in-turned, or the arm otherwise provided with a flange 26, tapering downwardly toward the top of the pile of advancing sheets, whereby the upwardly projecting portion of the advancing tape 9 is folded over the top of the pile 27 of the sheets to be taped, as best shown in Fig. 4. A notch or recess 28 is provided in the edge of the plate 11, permitting inward movement of the end of the spring arm 25 beyond the plane of the vertical portion 12 of the guide-way.

Should a pile of sheets be improperly directed into the feeding mechanism, in such manner that the edge thereof to be taped does not abut against the vertical portion 12 of the plate 11, or be slightly inclined horizontally from the plane of said vertical portion 12, the end edge of the arm 25, which is being yieldingly pressed against the flexible tape toward the edge of the pile of sheets being taped, will press the vertical portion of said tape against the side edge of the pile. In this manner, I insure substantially uniform contact between the end edges of the sheets being taped and the ver-

tical portion of the taping strip, the recess 28 permitting of the assembled sheets being followed by the spring-pressed arm 25 to insure adhesion throughout the entire area 5 of the taping strip.

From the end edge of the presser spring 25, the now partially taped books or pads pass under the rotary brush 29, which is tilted or inclined, as shown, in order that the 10 bristles 30 on the near side thereof will wipe or rub over the folded portion of the tape toward the edge thereof, while the bristles on the far side of said brush are raised clear of the tape in order that movement thereof 15 may not undo, or partially undo, the work which has been done by the effectively operating bristles on the near side of the brush. The brush 29 is rotated from the shaft 33 which is flexibly connected with the inclined 20 brush shaft in a common and well-known manner, the shaft 33 being rotated from the driving shaft 20 by means of a belt 31 passing around a pulley 32 on the latter and a pulley 32' on the former, all as shown and 25 described in the patent to Hren, aforesaid.

Furthermore, to insure against the possibility of reverse or undoing effect of the brush bristles on the far side of said brush, in addition to tilting or inclining the latter I provide 30 the flat leaf-spring 34, so curved or in-turned that the free end thereof is presented to the advancing pile of taped sheets, lying flat against the upper taped edge thereof. The end 35 of this spring 34 is sharply incurved 35 upon itself, as best shown in Fig. 3, to provide a rounded edge, so that it may not engage and obstruct or impede movement of the advancing work or partially detach the tape from the pad or pile before the adhesive has set.

This spring plate 34 is so located that the edge 35 is beneath the brush 29, in such position with relation thereto that at the point where the revolving bristles 30 start upon 45 their return movement toward the edge of the pad, they are lifted from the latter and carried along the base of said plate out of contact with the tape, and are therefore incapable of applying forces which might 50 otherwise tend to loosen or displace said tape.

I have found, however, that the brush 29 alone, while performing a most useful function, is not absolutely dependable as a means 55 for insuring substantially continuous adhesion between the tape and the work. To complete or perfect the taping operation, therefore, I prefer to pass the taped edge of the work over an idler roller 36 and under 60 presser roller 36', the latter being located at the end of the arm 37 pivoted on the pin 38, and being under yielding pressure from the spring 41 in compression between said arm 37 and the head 42 at the end of the adjusting screw 43. The roller 36' insures

complete and continuous adhesion of the tape to both sides of the edges of the books or pads which are being carried by the belts 14 and 14' to suitable mechanism for severing the tape-strip between adjacent pads or 70 books, and thus delivering the latter in a separated condition—this cut-off mechanism not being shown in the drawing as it forms no part of the present invention.

By means of the several improvements 75 hereinbefore described, I find that I can produce a high-grade product of uniformly superior qualities.

Many modifications of minor details of my improved tape-applying mechanism for 80 book-backing machines will doubtless readily suggest themselves to those skilled in the art to which it appertains, and I therefore do not desire to limit my invention to the specific construction herein shown and de- 85 scribed.

I claim as new and desire to secure by Letters Patent:

1. In a machine for backing books, tablets or the like, the combination, with means for 90 advancing substantially rectangular work units in continuous procession through the machine, of means for folding around corresponding side edges of the advancing units successively a continuous adhesive strip of 95 flexible material, said folding means including means for yieldingly pressing the advancing strip toward and against the contiguous edge of each unit in transit.

2. In a machine for backing books, tablets 100 and the like, the combination, with means for advancing substantially rectangular work units in continuous procession through the machine, of means for folding around corresponding side edges of the advancing units successively a continuous adhesive strip of 105 flexible material, said folding means comprising separate devices one of which also provides means for yieldingly pressing the advancing strip toward and against the contiguous edge of each unit in transit.

3. In a machine for backing books, tablets and the like, the combination, with means for advancing individual piles of assembled sheets successively into and through the machine, of yielding means for compacting the edge to be taped of each pile, means for folding around said compacted edges successively a continuous adhesive strip of flexible material, a portion of said folding means including means for yieldingly pressing said strip toward and against the edge of each pile prior to completion of the folding operation, and means for yieldingly pressing the tape edges against the sides of each pile 115 to insure continuous and uniform adhesive contact between said tape and the portions of the pile to which it is applied.

4. In a machine for backing books, tablets 120 and the like, the combination, with means

for advancing individual piles of assembled sheets successively into and through the machine, and means for correspondingly advancing a continuous adhesive strip of flexible material, of means for directing said strip to successive contact with corresponding side edges of the advancing piles, said directing means also operating to apply one edge of said strip to one side of the contiguous edge of each pile and rectangularly fold the remainder of said strip longitudinally for subsequent application of the other edge thereof to the other side of the edge of said pile, and means for completing the folding operation, said last-mentioned means being also yieldingly operable to press the middle portion of the tape in toward and against the edge of each pile in transit.

5. In a machine for backing books, tablets and the like, the combination, with means for advancing individual piles of assembled sheets successively into and through the machine, and means for correspondingly advancing a continuous adhesive strip of flexible material, of means for directing said strip to successive contact with corresponding side edges of the advancing piles, said directing means also operating to apply one edge of said strip to one side of the contiguous edge of each pile and rectangularly fold the remainder of said strip longitudinally for subsequent application of the other edge thereof to the other side of the edge of said pile, and means for completing the folding operation, said last-mentioned means comprising a guide-arm which is also spring-actuated toward said pile and which is provided with a vertical edge at the end thereof adapted to be yieldingly carried beyond the normal path of movement of the contiguous edge of said pile.

6. In a machine for backing books, tablets and the like, the combination, with means for advancing individual piles of assembled sheets successively into and through the machine, yielding means for compacting each pile at or near the edge thereof to be taped, and means for advancing a continuous strip of adhesive tape, of means for directing said tape to the compacted side edge of each pile in transit, said directing means also operating to apply one edge of said tape to one side of the contiguous edge of each pile and rectangularly fold the remainder of said tape longitudinally for subsequent application of the other edge thereof to the other side of the edge of said pile, means for completing the folding operation, said last-mentioned means being also operable to yieldingly press the middle portion of the tape toward and against the contiguous edge of each pile in transit, and means for yieldingly pressing the tape edges against the sides of each pile to insure continuous and uniform adhesive contact between said tape

and the portions of the pile to which it is applied.

7. In a machine for backing books, tablets and the like, the combination, with means for advancing substantially rectangular work units successively into and through the machine, and means for longitudinally applying adhesive tape around one side edge of each unit in transit, of a member rotatable about a substantially vertically disposed axis 75 and presenting a yielding face to the tape portion on one side of each pile in turn to exert rubbing pressure thereagainst, and means interposed between the tape and that shifting portion of said member, the general direction of rotation of which is from the edge toward the fold of the rubbed portion of said tape to intercept all rubbing forces which would otherwise be exerted in said general direction. 85

8. In a machine for backing books, tablets and the like, the combination, with means for advancing individual piles of assembled sheets successively into and through the machine, and means for longitudinally applying an adhesive tape around one side edge of each of said piles in transit, said means being adapted to first apply said tape to one side of the pile at its edge and subsequently fold said tape around said edge and upon the other side of said pile, of a member rotatable about a substantially vertically disposed axis and presenting a yielding face to the tape portion last applied to the pile to exert rubbing pressure thereagainst, and means interposed between the tape and that shifting portion of said member, the general direction of rotation of which is from the edge toward the fold of the rubbed portion of said tape to intercept all rubbing forces which would otherwise be exerted in said general direction. 95

9. In a machine for backing books, tablets and the like, the combination, with means for advancing individual piles of assembled sheets successively into and through the machine, and means for longitudinally applying adhesive tape around one side edge of each pile in transit, of a member rotatable about a substantially vertically disposed axis 110 and presenting a yielding face to the tape portion on one side of the pile to exert rubbing pressure thereagainst, said member being slightly tilted to raise the shifting side thereof which is moving over the pile toward the edge thereof, and means interposed between the raised side of said member and said tape to positively intercept and receive all rubbing forces on this side of said member. 115

10. In a machine for backing books, tablets and the like, the combination, with means for advancing individual piles of assembled sheets successively into and through the machine, and means for longitudinally 120

applying an adhesive tape around one side edge of each of said piles in transit, said means being adapted to first apply said tape to one side of the pile-edge and subsequently

the rubbed portion of said tape to raise clear of the latter the bristles not moving in such general direction. 35

- 5 fold said tape around said edge and upon the other side of said pile, of a member rotatable about a substantially vertically disposed axis and presenting a yielding face to the tape portion last applied to the pile to exert rubbing pressure thereagainst, said member being slightly tilted to raise the shifting side thereof which is moving over the pile toward the edge thereof, and means interposed between the raised side of said member and
- 10 15 said tape to positively intercept and receive all rubbing forces on this side of said member.

12. In a machine for backing books, tablets and the like, the combination, with means for advancing individual piles of assembled sheets successively into and through the machine, and means for longitudinally applying a strip of adhesive tape around one side edge of each of said piles in transit, said

40

- 20 25 fold said tape around said edge and upon the other side of said pile, of a brush rotatable about a substantially vertically disposed axis and having bristles on the side thereof presented to the tape portion last applied to the pile being taped and adapted to wipe said portion, and means interposed between said

45

30 35 tape and that shifting portion of said brush the general direction of rotation of which is from the edge toward the fold of the rubbed portion of said tape to raise clear of the latter the bristles not moving in such general direction. 50 55

In testimony of the foregoing, I have hereunto set my hand in the presence of two witnesses.

LEONARD J. FROHN.
